UNITED STATES PATENT OFFICE.

HERBERT K. RANDALL AND STACY C. THOMPSON, OF MANISTEE, MICHIGAN.

RACK.

1,038,198.

Specification of Letters Patent. Patented Sept. 10, 1912.

Application filed March 30, 1912. Serial No. 887,429.

To all whom it may concern:

Be it known that we, HERBERT K. RANDALL and STACY C. THOMPSON, citizens of the United States, residing at Manistee, in the county of Manistee and State of Michigan, have invented certain new and useful Improvements in Racks; and we do hereby declare the following to be a full, clear, and exact description of the invention, such as will enable others skilled in the art to which it appertains to make and use the same.

This invention relates to an improvement in racks,—one object of the invention being to provide a knockdown rack having radiating arms, and to so construct the device that the parts can be quickly assembled and form a rigid and substantial structure, without the necessity for use of metallic fastening devices.

26 A further object is to so construct the rack that it can be readily adapted for use as a clothes drier, ironing-rack or a clothes or hat tree.

25 A further object is to so dispose the radiating arms of the rack that a considerable number of them can be employed without arranging superimposed arms in vertical alinement with each other, thus avoiding conflict between articles hung on certain of

30 said arms with lower arms.

With these objects in view the invention consists in certain novel features of construction and combinations of parts as hereinafter set forth and pointed out in the claim.

In the accompanying drawings, Figure 1 is a view of a rack embodying our improvements, when used as a clothes drier. Fig. 2 is a view illustrating the application of the device as a clothes or hat tree, and Figs. 3, 4, 5 and 6 are detail views.

1 represents a base comprising horizontally disposed supporting legs 2 which are provided centrally with notches 3 to permit said supporting legs to be interlocked when they are disposed at right angles to each other, and each supporting leg is provided at its respective ends with depending portions 4 in which castor wheels are mounted. The base 1 supports a standard 5, the lower portion of which is made square in cross section and this square lower end of the standard is provided with slots 7 in its several sides and said slots are made to communicate with each other. The

standard thus formed is placed on the center of the base 1 so that the legs thereof will enter the slots 7 in the base of said standard and thus the legs will be tied together by the standard and the latter will be effectually secured to the base without necessity for the use of metallic fastening means. The standard 5 is made in two sections 8—9, the lower section being provided at its upper end with a plurality of notches or slots 10 to receive a corresponding number of ribs 11 which depend from the upper section 9,—said notches or slots and ribs being so proportioned that when the two sections of the standard are joined, the continuity of the surface of the standard at the joint will be maintained. The body of the standard above the lower angular portion thereof may conveniently be made cylindrical in form (or round in cross-section) and said angular lower portion might also be made of the same shape if desired.

The standard is provided with several series of sockets 12 for the reception of radiating arms 13 to support clothes to be dried, or to receive short arms or pins 14 when the device is to be used as a clothes or hat tree. Each series of sockets is spirally arranged and each spirally arranged series begins near the upper portion of the standard and terminates near the lower portion thereof at a point diametrically opposite the part of the standard where the first upper socket of the series is located. In forming these spiral, or rather half spiral series of sockets, the upper socket of each series is located farther away from the upper end of the standard than the upper sockets of the other series. We prefer to employ four such partly spiral series of sockets so that when the supporting arms 13 or 14 are secured in the sockets, none of said supporting arms will be disposed in vertical alinement with others and hence articles hung on one arm will not conflict with other arms of the rack.

In the drawings we have illustrated our improvements as adaptable for use as a clothes drier and as a clothes or hat tree. When the device is to be used as an ironing rack,—viz: to receive clothes just after they have been ironed,—the upper section of the standard and the arms thereon will be removed.

Having fully described our invention

what we claim as new and desire to secure by Letters-Patent is,—

A knock-down rack comprising a base embodying intermeshing leg portions disposed at an angle to each other, a standard having intermeshing connection with the base at the juncture of the legs thereof, said standard comprising a plurality of superimposed sections having removable interlocking connection with each other, and ra-

diating arms removably connected with said standard.

In testimony whereof, we have signed this specification in the presence of two subscribing witnesses,

HERBERT K. RANDALL.
STACY C. THOMPSON.
